Primary Examiner — Catherine S Posthauer(74) *Attorney, Agent, or Firm* — Sanchelima & Associates, P.A.; Christian Sanchelima; Jesus Sanchelima(57) **CLAIM**

The ornamental design for a coffee cup lid, as shown and described.

DESCRIPTION

FIG. 1 is an isometric view of a coffee cup lid showing my new design in a position of use with an exemplary coffee cup;

FIG. 2 is a front elevational view thereof, shown with the exemplary environmental subject matter of a coffee cup removed;

FIG. 3 is a rear elevational view thereof;

FIG. 4 is a left side elevational view thereof;

FIG. 5 is a right elevational view thereof;

FIG. 6 is a top plan view thereof; and

FIG. 7 is a bottom plan view thereof showing my design; and,

FIG. 8 is an isometric view.

The broken lines are shown for the purpose of illustrating parts of the article as well as environmental subject matter of an exemplary coffee cup. None of the broken lines form part of the claimed design.
